UNITED STATES PATENT OFFICE.

WILBUR H. YOUNG, OF KEYPORT, NEW JERSEY.

ELECTRICAL CONNECTION.

1,308,214.

Specification of Letters Patent.

Patented July 1, 1919.

Application filed March 19, 1913. Serial No. 755,469.

To all whom it may concern:

Be it known that I, WILBUR H. YOUNG, a citizen of the United States of America, residing in Keyport, in the county of Monmouth, State of New Jersey, have invented certain new and useful Improvements in Electrical Connections, of which the following is a specification.

This invention relates to pigtail brushes for electrical machines and more particularly to a novel electrical connection, or "pig tail", and to the manner of fastening the same to the brush.

The object of the invention is to provide a cheaply manufactured and efficient connection that can be easily and quickly applied to a brush and can be repeatedly used with new brushes as the old brushes wear out.

To this end I have provided a connection or pig tail having an inner expansible terminal adapted to be tightly expanded in an opening, without special form, provided in the brush, thus forming an efficient electrical contact with the brush.

This terminal is adapted to be repeatedly expanded and contracted, whereby it is adapted to be used with new brushes—as the old ones wear out—as many times as desired.

In the accompanying drawing, showing, by way of example, several of many possible embodiments of the invention:

Figure 1 shows a brush, partly in section, and an axial sectional view of one form of a connection terminal applied to the brush, part of the connection being shown in elevation;

Fig. 2 is a sectional view taken on the line 2—2 of Fig. 1;

Fig. 3 is a side elevation of the terminal in expanded condition;

Fig. 4 is a side elevation of the terminal, contracted and ready to be applied to a brush;

Fig. 5 shows an axial section of another form of terminal;

Fig. 6 shows a section taken on the line 6—6 of Fig. 5, and

Fig. 7 shows an axial sectional view, partly in elevation, of another form of the invention;

The terminals illustrated in Figs. 1 to 7 comprise resilient corrugated split sleeve 10 adapted to be expanded in the bore 11 provided at any convenient point in the brush 12. This bore may be drilled with any ordinary standard twist drill of the required size.

All of the terminals shown are provided with a flexible cable 14 having an outer clip, 15.

Referring more particularly to Figs. 1 to 4, the inner end of the cable 14 has pinched or otherwise secured thereon an end expanding cone 16; while slidable on an intermediate part of the cable is a movable expanding cone 18; both cones having their smaller ends pointing toward each other.

The terminal is assembled with its parts as shown in Fig. 4, and as thus arranged the elasticity of the sleeve contracts it to its smallest diameter, and the terminal is ready to be inserted in the bore 11 of the brush, after which the expanding cones are driven toward each other, by pressure on the movable cone, and the parts of the terminal assume the relation shown in Figs. 1 to 3, the sleeve being tightly expanded against the walls of the bore and effecting therewith good electrical contact.

In the form of the invention illustrated in Figs. 5 and 6, the end expanding cone 26, pinched or soldered on the end of the cable, has an outer conical surface with the smaller end pointing toward the slidably split expander 28 which has an inner conical surface 29 adapted to receive the outer conical surface of the end cone 26. The parts being assembled as shown, the terminal may be readily expanded in the bore 11 of the brush by driving the parts 26 and 28 nearer together.

It is to be noted that the parts 26 and 28 may both be split and may be made of strips of spring metal.

In the form of terminal shown in Fig. 7, the end cone 36 is the movable cone and has screw threaded engagement with the stem 37 which may be integral with or otherwise secured to the fixed cone 38 provided with an engaging portion 39 by which the cone 38 may be turned, by a suitable tool or by hand, to cause the cones 36 and 38 to move nearer together and expand the sleeve 10 or to move apart and cause the sleeve to contract. By this arrangement, the terminal may be secured in the bore or removed therefrom. The cable 14 may be soldered in a hole in the larger end of the cone 38.

The terminal illustrated in Fig. 7 may be removed from the brushes, when renewing the brushes, by manipulating the terminals

as explained. In all the forms of the invention, when a brush is worn out, it can be broken off from the terminal, and the terminal applied to a new brush.

5 The various parts of the electrical connections forming the subject of this invention may be made of copper, brass or any material which may be found suitable, and the said connections may be used for forming any connections for which they may be found suitable.

10 While herein I have described minute details of the invention, the invention is not limited to these; and the details of construction, arrangement and operation may be greatly varied without departing from the spirit and scope of the invention as claimed.

I claim as my invention:

20 1. An electrical connection comprising an elastic one-piece split sleeve of approximately constant diameter; a pair of inwardly pointing inter-engaging cones in said sleeve; and a flexible conductor permanently connected to one of said cones and along which the other cone is adapted to slip for assembling the connection.

25 2. An electrical connection comprising a pair of inter-engaging one-piece cones; and 30 a conductor passed axially through said cones and having one end permanently secured to the inner cone, the conductor being freely flexible, whereby the outer cone can

freely slide upon the conductor and the assembled connection inserted in a bore closed 35 at one end, and the connection then tightened, the outer cone being elastic.

3. An electrical connection comprising a pair of inter-engaging one-piece cones; and a conductor passed axially through said 40 cones and having one end permanently secured to the inner cone, the conductor being freely flexible, the outer cone being elastic.

4. An electrical connection comprising an electrical conductor having a cylindrical 45 opening, closed at one end and of substantially uniform diameter; a pair of inter-engaging one-piece cones entirely within the opening; and a freely flexible conductor passing through one cone and secured to 50 the other, said cones being adapted for insertion within the opening while they are assembled on the flexible conductor.

5. An electrical connection comprising an elastic one-piece split sleeve; a pair of inwardly pointing cones therein; a freely flexible cable passing axially through both cones and secured directly to one of the cones.

55 In testimony whereof I hereto affix my 60 signature in the presence of two witnesses.

WILBUR H. YOUNG.
